UNITED STATES PATENT OFFICE.

PAUL RICHERT, OF NEW YORK, N. Y., ASSIGNOR TO PITTSBURGH TAXIMETER COMPANY, A CORPORATION OF PENNSYLVANIA.

TAXIMETER.

Substitute for application Serial No. 703,898, filed April 3, 1924. This application filed February 4, 1925. Serial No. 6,698.

This invention relates to recording and indicating devices and more particularly to taximeters of the type shown, for example, in my prior Patent No. 1,522,910 of January 5 13, 1925, and this application is a substitute for my earlier filed application No. 703,898 of April 3, 1924.

In the said patent I have shown a taximeter in which the fare indicating dials are adapted to be driven either by movement of the vehicle, on which the meter is mounted, or by a clockwork mechanism embodied within the meter.

In certain localities regulations require an initial waiting period between the time the vehicle reaches the address called and the time the meter begins to register. This, of course, is only when the vehicle is kept waiting for a passenger after having been engaged 20 and when it is not immediately put in use. In order to eliminate the element of personal carelessness on the part of the driver in determining the length of time the vehicle has been kept waiting the meter shown in my said 25 patent is provided with a lost motion device in the clock driven mechanism whereby the fare indicating dials are not actuated by the clock driven mechanism for four minutes after the flag shaft is moved to the "hired" 30 position, this being the length of initial waiting period required by regulations in a large number of localities. The meter shown in the said patent may be termed "a four minute meter", in that it is provided with a sufficient 35 amount of lost motion in the clock driven mechanism to allow for exactly four minutes between the time the flag shaft is placed in the "hired" position and the time the fare indicating dials are actuated.

40 However, in some places the initial waiting period is substantially greater than four minutes. This requires an increased amount of lost motion in the clock driven mechanism and accordingly an increase in the amount of 45 movement of the parts which is necessary to properly set the lost motion device at the beginning of the period of hire. The "four minute meter" of the said patent is not adapted to properly set the parts where the extent 50 of lost motion is increased to provide for a waiting period of say six minutes and an object of this invention is to provide a meter having means for insuring the proper setting of the lost motion device at the beginning of 55 a period of hire regardless of the amount of

lost motion in the clock driven mechanism and to thus provide a meter which can be adapted to any required length of initial waiting time by merely changing the amount of lost motion in the clock driven mechanism. 60

A further object is to provide a meter in which all backlash between the gears of the clock driven gear train is eliminated so that when the vehicle on which the meter is mounted comes to a stop the clockwork mechanism 65 will immediately take up the drive of the fare indicating dials without having to first make up for any lost motion due to backlash in the clock driven gear train.

A still further object is to provide a meter 70 of the type set forth which will accurately register the correct fare and at the same time be simple and rugged in construction.

These and other objects which will appear obvious to those skilled in the art, are attained by means of this invention, one embodiment of which is shown, for the purposes of illustration, in the accompanying drawings in which Figure 1 is a vertical sectional view of a meter embodying this invention 75 showing the operating elements in elevation, Fig. 2 is a similar view of the upper half of the meter showing the parts in operatively connected relation, Fig. 3 is a horizontal section showing the lost motion device in plan, 80 Fig. 4 is an elevation of the lost motion device, Fig. 5 is a partial view similar to Fig. 3 with certain of the elements omitted, Fig. 6 is a view similar to Fig. 1 taken on a different plane and Fig. 7 is an elevation of the backlash eliminator and the disengaging lever therefor. 90

In the drawings I have illustrated a meter having a fare indicating mechanism comprising interconnected fare indicating dials, 95 an actuating mechanism therefor which is intermittently operated by a rotating ratchet wheel so as to operate the fare indicating dials in accordance with the movement of the vehicle or with the length of time the vehicle is hired in case it is kept waiting. The driving ratchet is operated either by movement of the vehicle or by a clockwork mechanism embodied within the meter. The clock driven mechanism is provided with a lost motion device of sufficient extent to allow for the correct amount of initial waiting time as required by local regulations, as above described. The connection and disconnection of the fare actuating mechanism with 100 105 110

the driving ratchet is controlled by movement of the flag shaft through a control or master lever. The lost motion device is properly set at the beginning of its stroke by 5 rotation of the driving ratchet before the latter is operatively connected to the actuating mechanism and in order to insure sufficient rotation thereof so as to properly set the lost motion device at the beginning of its movement regardless of the amount of lost motion 10 that it may be necessary to provide for an increased initial waiting period, there is provided an auxiliary or booster lever which is operated by movement of the flag shaft to 15 rotate the driving ratchet, and thus properly set the lost motion device, just prior to the connection of the fare actuating mechanism with the driving ratchet.

As illustrated this invention includes a 20 back plate 1 on which is supported the entire meter mechanism within a suitable housing 2 secured to the back plate. A supporting plate 3 is mounted in spaced relation to the back plate 1 by means of suitable pins 4 and supported from the plate 3 are the usual fare indicating dials 5, 6 and 7 connected by interrupted gears (not shown) and mounted on shafts 8, 9 and 10, respectively, as is well known in the art.

30 The fare indicating dials are actuated through a ratchet 11 mounted on the shaft 8 of the tens dial 5. A master or control lever 12 is pivotally mounted at 13 upon the back of the plate 3 and is provided with a stub shaft 14 which extends forwardly through an opening 14' formed in the plate 3. A lever 15 is pivotally mounted upon the stub shaft 14 adjacent the front face of the plate 3 and is provided with a cam surface or tooth 35 16 for engagement with the ratchet wheel 17 mounted on a shaft 18 which is journaled in the plate 3 and extends rearwardly therefrom. A spring 19 secured to one arm of the lever 15 normally maintains the tooth 16 in 40 yielding engagement with the teeth of the ratchet wheel. A downwardly extending pawl 20 is pivotally mounted upon the other arm of the lever 15 by means of a pin 21 and is yieldingly maintained in engagement with 45 the ratchet wheel 11 by a spring 22.

50 It will thus be seen that rotation of ratchet wheel 17 oscillates the lever 15 about its supporting pivot on the master or control lever 12 which in turn produces an intermittent 55 rotation of the tens dial 5 through operation of the pawl 20 and the ratchet 11. On every complete revolution of the tens dial 5 the dial 6 will advance one step and upon every revolution of the dial 6 the dial 7 will advance 60 one step, all as is well known in this particular art.

The meter is provided with a flag shaft 23 which is adapted to be operated by the driver of the vehicle in the well-known manner. A 65 cam 24 is secured to the cam shaft and upon

rotation thereof engages the cam face 25 formed on the upper end of the master lever 12 so as to rotate the lever about its supporting pivot 13. Also secured to the flag shaft 23 is a disc cam 26. A lever 27 is pivoted at 70 28 on the plate 3 and one arm thereof is provided with a pin 29 adapted to ride upon the surface of the cam 26 with which it is maintained in contact by a suitable spring 30. When the cam 26 is moved so that the pin 29 is in the low portion thereof the spring 30 causes the arm 27 to assume the position shown in Fig. 1. In this position the upper arm of the lever 27 contacts with the pin 21 on the lever 15 and raises the latter so as to disengage the cam surface or tooth 16 thereof from the driving ratchet 17, this being the "not hired" position of the meter. The master lever has been rotated to the left by the cam 24 so as to cause disengagement of the indicating dials and actuation of the cancelling mechanism as more fully described and claimed in my prior Patent No. 1,522,910 of January 13, 1925, the description of which is omitted from the present application as it has no bearing upon this invention.

75 When the vehicle is in motion the ratchet 17 is driven by rotation of the shaft 18 by means of the following mechanism. A vertical worm shaft 32, mounted in suitable bearings 33 on the back of plate 3, is connected through the usual well-known flexible driving shaft (not shown) with a moving part of the vehicle. The upper end of this worm shaft is provided with a worm 34 which drives a worm wheel 35 mounted upon the shaft 18 for driving connection therewith, when rotated in one direction, and for free movement thereon when rotated in the opposite direction, through the medium of a suitable ball clutch mechanism 36 which may be of any desired construction. Rotation of the shaft 32 by movement of the vehicle thus rotates the shaft 18 and the driving ratchet 17 so 100 as to actuate the lever 15 and pawl 20 and operate the fare indicating dials, when the meter is in the "hired" position, shown in Fig. 2.

105 In order that the meter will function during a period when the vehicle is hired but not in motion there is provided a clockwork mechanism 37 provided with the usual gear 38 which meshes with and drives a pinion 39 secured to a shaft 40 which is journaled at its 110 respective ends for axially slidable movement in the plate 3 and a supporting plate 41. A gear 42 loosely mounted on the slidable shaft 40 meshes with and drives a gear wheel 43 mounted upon the shaft 18 with which it is 115 connected for driving in one direction by a suitable ball clutch mechanism 44, similar to the ball clutch mechanism 36. A suitable overhanging finger 45 mounted on the supporting plate 3 maintains the gear 42 in mesh 120 125 130

with the gear 43 during axial sliding movement of the shaft 40. The gear 42 has a hub portion 46 which is provided with a relatively deep slot 47 formed with a relatively narrow portion 48 and a wide portion 49. The shaft 40 has a pin 50 received within the slot 47 so that rotation of the shaft 40 will drive the gear 42. When the vehicle is in motion during a period of hire the worm shaft 32 will rotate the gear 35 and ratchet 17 so as to actuate the fare indicating mechanism, (the pin 50 on the shaft 40 being ordinarily maintained in the narrow portion of the slot 47). When the vehicle comes to a stop the worm shaft 32 will stop but the driving ratchet 17 will continue to be rotated through the medium of the clockwork mechanism and the gears 42 and 43 just described.

The shaft 40 has a beveled forward end 52, see Fig. 3, which projects slightly beyond the supporting plate 3. A lever 53 is pivoted at 54 to the plate 3 and is provided at one end with a cam face 55 adapted to cooperate with the beveled end of the shaft 40. A spring 56 tends to hold the cam face 55 away from the end 52 of the shaft 40. A pin 57 on the master lever 12 contacts with the other arm of the lever 53 so that when the meter is in the "not hired" position, see Fig. 1, the lever 53 is moved against the tension of the spring 56 and the cam face 55 engages the beveled end 52 and moves the shaft 40 rearwardly so as to place the pin 50 in the wide portion 49 of the slot 47. Obviously when the pin 50 is in the wide portion of the slot 47 a certain amount of lost motion exists between the shaft 40 and the gear 42 which must be taken up before the gear 43 and ratchet 17 will be rotated by the clockwork mechanism 37.

40 A lever 58 is pivoted to a bracket 59 mounted upon the back of the auxiliary supporting plate 41. One arm of the lever 58 engages the rear end of the shaft 40 and the other arm thereof is adapted to be engaged by a finger 60 which is frictionally mounted upon the worm shaft 32 by means of a suitable spring 61. Whenever the vehicle is in motion the rotation of the worm shaft 32 presses the finger 60 against the adjacent end of the lever 58, causing the same to oscillate about its pivot so that its other arm presses the shaft 40 forwardly and moves the pin 50 into the narrow portion 48 of the slot 47 thus removing all lost motion between the clockwork mechanism and the driving ratchet 17. As soon thereafter as the vehicle is brought to rest and the worm shaft 32 becomes stationary the clockwork 37 rotates the ratchet 17 through the described connection.

65 When the mechanism is moved to the "not hired" position the lever 12 and pin 57 are moved by the cam 24 so as to cause the lever 53 to oscillate about its pivot and bring the cam face 55 into contact with the beveled end 52 of the shaft 40, moving the latter rear-

wardly and the pin 50 into the wide portion 49 of the slot 47.

As soon as the meter mechanism is set to function during a period of hire, the lever 53 is released and the spring 56 moves the same out of engagement with the end 52 of the shaft 40. If the vehicle is stationary at the time, the shaft 32 and finger 60 remain motionless and the shaft 40 is not moved. The clockwork mechanism, however, drives the shaft 40 through the medium of the gear 30 and pinion 39. By reason of the fact that the shaft 40 has not yet been moved axially, the pin 50 is disposed in the wide portion of the slot 47 in the hub 46 and a certain amount of lost motion therefore exists between the shaft 40 and the gear 42. The amount of this lost motion is determined by the width of the wide portion 49 of the slot 47 and varies according to the regulations regarding the length of the initial waiting period under which the vehicle is operated.

It is essential to insure the positioning of the pin 50 in the proper end of the wide portion 49 of the slot 47 at the beginning of a period of hire as otherwise the amount of lost motion and therefore the extent of the initial waiting period will be decreased. This is done by means of a lever 65 pivoted at 66 to the forward face of the plate 3. The lever has a downwardly extending inwardly curved arm 67 having a pawl 68 secured to the inner end thereof and adapted to engage the teeth of the ratchet wheel 17 upon movement of the lever 65. A pin 69 is mounted on the back face of the cam 26 and is adapted to engage the other arm of the lever 65 so as to oscillate the same about the pivot 66. Movement of the flag shaft 23 from the "not hired" to the "hired" position causes the pin 69 to oscillate the lever 65, as shown in the full and dotted line positions in Fig. 2. Movement of the lever rotates the ratchet 17 and through it the shaft 18. Although the direction of rotation of the shaft is such as to cause disengagement of the ball clutch 44 and gear 43 therewith, the frictional drag of the clutch members is sufficient to cause the gears 43 and 42 to rotate therewith in the absence of any material resistance to such movement. This rotation of the gear 42 continues until the pin 50 on the shaft 40 engages with the edge of the slot 47. Upon the pin 50 striking the edge of the slot further rotation of the gears 42 and 43 is prevented and the ratchet 17 and shaft 18 may continue to rotate under the impulse of the lever 65 due to the slip of the ball clutch 44. The above described operation, of course, takes place before the flag shaft 23 has moved far enough to place the lever 15 in operative contact with the ratchet 17.

By providing the lever 65, any practical amount of lost motion can be accommodated and the device properly set at the beginning

of a period of hire. The only changes necessary to adapt the meter to different regulations in regard to the initial waiting period is a change in the width of the wide portion 5 of the slot 47.

After the vehicle is set in motion and the finger 60 and lever 58 have moved the pin 50 into the narrow portion of the slot 47 it is necessary to prevent all lost motion between 10 the different gears of the gear train driven by the clockwork mechanism in order to have a perfectly accurate meter. This necessitates elimination of all backlash between the 15 gears forming the gear train driven by the clockwork mechanism.

A lever 70 is pivoted at 71 on the rear face of the plate 3 adjacent the gear 43. This lever has a tooth 72 engaging the teeth of the gear 43 with which it is held in yielding contact by a spring 73. The lever and tooth are so formed as to yieldingly resist rotation of the gear 43 under the clockwork drive. This backward pressure prevents all lost motion or backlash between the gears of the gear 20 train so that when, during a period of hire, the vehicle comes to a stop, or to a speed so slow that the clockwork mechanism drives the fare indicating mechanism ahead of the vehicle drive, the clockwork mechanism will 25 immediately take hold and continue rotation of the ratchet 17 without having to first make up for any backlash in the clock driven gear train. This prevents any momentary cessation of operation of the actuating mechanism when the vehicle comes to a stop and 30 insures an absolutely accurate meter.

It is, of course, necessary to disengage the lever 70 from the gear 43 to enable the setting of the lost motion connection by the 40 booster lever 65, when the flag shaft is rotated from the "not hired" to the "hired" position. This is accomplished by means of a cam lever 75 having an inclined cam surface 76 adapted to engage a cooperating pin 45 77 extending outwardly from the lever 70 so as to move the latter upon its supporting pivot 71 and disengage the lever and gear 43. The cam lever is formed integrally with the hub of the arm 60 and is movable therewith.

The disengagement is accomplished when 50 the flag shaft is moved to the "not hired" position. As above described the lever 53 at that time contacts with the end 52 of the slidable shaft 40, forcing the latter rearwardly and oscillating the lever 58 so as to move the arm 60 about the worm shaft 32, see Figs. 3 and 7. This, of course, moves the cam surface 76 of lever 75 against the pin 77 so as to force the lever downwardly away from the 55 gear 43. The latter is then free of the lever's drag so that it may be easily rotated by the booster lever for setting the lost motion device when the flag shaft is next moved into the "hired" position.

65 I claim:

1. In a taximeter, the combination of a fare indicating mechanism, means for actuating said mechanism, a ratchet for operating said actuating means, a clock-work mechanism adapted to drive said ratchet, a driving connection between said clock-work mechanism and said ratchet, including a lost motion device, a flag shaft adapted to connect and disconnect said ratchet and said actuating means and a lever operated by said flag shaft for rotating said ratchet while disconnected from said actuating means so as to set said lost motion device to permit said clock-work mechanism to operate for a predetermined period of time before driving said ratchet after it is connected to said actuating means. 70

2. In a taximeter the combination of a fare indicating mechanism, means for actuating said indicating mechanism, a ratchet for operating said actuating means, a clockwork mechanism adapted to drive said ratchet, a driving connection between said clockwork mechanism and said ratchet including a lost motion device, a flag shaft adapted to connect and disconnect said ratchet and said actuating means and means operatively associated with said flag shaft for rotating said ratchet so as to set said lost motion device to permit said clockwork mechanism to operate for a predetermined period of time before moving said ratchet for actuating said indicating means. 75

3. In a taximeter the combination of a fare indicating mechanism, means for actuating said indicating mechanism, a ratchet for operating said actuating means, a clockwork mechanism adapted to drive said ratchet, a driving connection between said clockwork mechanism and said ratchet including a lost motion device, a flag shaft adapted to connect and disconnect said ratchet and said actuating means and means for rotating said ratchet while disconnected from said actuating means so as to set said lost motion device to permit said clockwork mechanism to operate for a predetermined period of time before driving said ratchet after it is connected to said actuating means. 100

4. In a taximeter the combination of a fare indicating mechanism, means for actuating said indicating mechanism, a ratchet for operating said actuating means, a clockwork mechanism adapted to drive said ratchet, a driving connection between said clockwork mechanism and said ratchet including a lost motion device, a flag shaft adapted to connect and disconnect said ratchet and said actuating means and a pawl operated by said flag shaft for rotating said ratchet so as to set said lost motion device to permit said clockwork mechanism to operate for a predetermined period of time before moving said ratchet for actuating said indicating means. 105

5. In a taximeter for vehicles, the combination of a fare indicating mechanism, means 110

- for actuating said indicating mechanism, means operated by movement of the vehicle for driving said actuating means, a clock-work mechanism including a gear train for driving said actuating means when said vehicle is at rest and a lever adapted to engage a gear in said train for yieldingly resisting movement of said gear train and eliminating backlash therefrom so as to prevent momentary cessation of operation of said actuating means when the vehicle comes to a stop. 25
6. In a taximeter for vehicles the combination of a flag shaft, a fare indicating mechanism, means for actuating said indicating mechanism, means operated by movement of the vehicle for driving said actuating means, a clockwork mechanism adapted to drive said actuating means when the vehicle is at rest, a gear train connecting said clockwork and said actuating means including a lost motion device, a lever having a tooth adapted to engage a gear in said train so as to eliminate backlash in said train and prevent momentary cessation of operation of said actuating means 30 when the vehicle comes to a stop and a cam for disengaging said lever from said gear to permit setting of said lost motion device. 35
- 10 7. In a taximeter for vehicles the combination of a fare indicating mechanism, means for actuating said indicating mechanism, means operated by movement of the vehicle for driving said actuating means, a clock-work mechanism adapted to drive said actuating means when the vehicle is at rest, a gear train connecting said clockwork and said actuating means including a lost motion device, means adapted to engage a gear in said gear train for yieldingly resisting movement thereof so as to prevent momentary cessation 40 of operation of said actuating means when the vehicle comes to a stop and a cam for disengaging said lever from said gear to permit setting of said lost motion device. 45
- 15 20

In testimony whereof, I have hereunto subscribed my name this 30th day of January, 1925.

PAUL RICHERT.
